Filed Feb. 17, 1967, Ser. No. 5,853

Term of patent 14 years

Int. Cl. D9—01

U.S. Cl. D9—46

FIG. 1 is a side elevation view of a combined milk bottle and carrying handle showing my new design, the opposite side being a mirror image thereof;

FIG. 2 is a top view on an enlarged scale of the combined milk bottle and carrying handle illustrated in FIG. 1;

FIG. 3 is an elevation view on a still larger scale from FIGS. 1 and 2 showing the neck and finish portions of the combined milk bottle and carrying handle;

FIG. 4 is a horizontal view on a reduced scale from FIG. 3, partially in section, taken along the line 4—4 of FIG. 3 with the lower portions thereof omitted for convenience of illustration;

FIG. 5 is a fragmentary, horizontal section view on a reduced scale from FIG. 3, taken along the line 5—5 of FIG. 4; and

FIG. 6 is a fragmentary, elevation view on a reduced scale from FIG. 3 of the combined milk bottle and carrying handle looking from the left-hand side of FIG. 3.

The dominant features of my design reside in the portions shown in full lines.

I claim:

The ornamental design for a combined milk bottle and carrying handle, as shown and described.
